(57) **CLAIM**

I claim the ornamental design for a fixed angle cutting tool sharpening aid, as shown and described.

DESCRIPTION

FIG. 1 is a rear, right, and top perspective view of a fixed angle cutting tool sharpening aid placed on a blade of a cutting tool;

FIG. 2 is a rear, left, and top perspective view of the fixed angle cutting tool sharpening aid;

FIG. 3 is a front elevational view of the fixed angle cutting tool sharpening aid;

FIG. 4 is a rear elevational view of the fixed angle cutting tool sharpening aid;

FIG. 5 is a right side elevational view of the fixed angle cutting tool sharpening aid;

FIG. 6 is a left side elevational view of the fixed angle cutting tool sharpening aid;

FIG. 7 is a top plan view of the fixed angle cutting tool sharpening aid; and,

FIG. 8 is a bottom plan view of the fixed angle cutting tool sharpening aid.

The broken line showing of a cutting tool and surface in FIG. 1 illustrate environment only and forms no part of the claimed design. The broken line showing of a sinuous edge illustrates the boundary of the unclaimed environment and forms no part of the claimed design.
